PAPER MAKING APPARATUS

Filed May 11, 1932

UNITED STATES PATENT OFFICE

WILLIAM R. KELLETT, OF MENASHA, WISCONSIN, ASSIGNOR TO PAPER PATENTS COMPANY, OF NEENAH, WISCONSIN, A CORPORATION OF WISCONSIN

PAPER MAKING APPARATUS

Application filed May 11, 1932. Serial No. 610,545.

This invention relates to paper making machines in which felts are used for picking up the web. Water is used as a shower for cleaning the felt or felts, which have been quite saturated. If the felt or felts carry any considerable amount of water, part of this excess water will tend to go into the web and is difficult to remove. The speed of the machine is therefore limited by drying capacity due to the large amount of water which the felt itself carries. The web can be no drier than the felt which is carrying it, and every pound of water that can be removed from the felt represents a gain in the drying speed and capacity of the machine.

The object of the present invention has been to effect an improved wringing or drying of the felt or felts at high speeds, while still maintaining the use of adequate water, which not only keeps the felt or felts clean but gives longer running life because of the lubrication which excess water affords in contact with felt-carrying rolls.

Briefly stated, the present invention resides in the application of suction press rolls to the felt in advance of the point of pick-up of the web by the felt. The invention may be employed to advantage on either single felt or double felt machines.

In the accompanying drawing, in which the figure is a diagrammatic side elevation, I have shown the invention applied to a Yankee paper making machine of the double felt type.

Referring to the drawing, 1 indicates a head box from which the paper stock flows on the usual Fourdrinier forming wire 2. Said forming wire is trained around a breast roll 3 and a couch roll 4, passing over the usual table rolls 5 and suction boxes (not shown) if desired. The web is designated by 6.

An upper felt 7 is trained around an upper couch roll 8, a transfer roll 9 that delivers the web to the drying drum 10, and suitably placed guide rolls 11, 12, 13, 14, 15 and 16. It picks up the web at the nip of the couch rolls 4 and 8. A shower 17 applies a spray of cleaning water to the

upper felt at a point between the transfer roll 9 and guide roll 11.

A lower felt 18 is trained over suitably placed guide rolls 19, 20, 21, 22 and 23. It engages the web at the nip of suction press rolls 24, between which latter the upper felt 7 and the web 6 also pass; the two felts, with the web between them, passing thence over the guide roll 19, at which point the lower felt 18 leaves the web. A shower 25 applies a spray of cleaning water to the lower felt at a point between the guide rolls 21 and 22.

The machine as thus far described, including the suction press rolls 24 located as described, is old and known. Suction presses, such as 24, have commonly been used to remove water from the felts and paper web simultaneously during the course of travel of the felts and web between the rolls, an example of a suction roll being disclosed in patent to Berry No. 1,679,598, August 7, 1928.

In the present invention, in order to remove excess water from the felts in addition to that removed from the felts and web by the suction press rolls 24 and before the felts, after cleaning, have contacted with the web, I employ similar suction presses on either or both of the felts. For example, I have shown an upper pair of suction press rolls 26 through which the upper felt 7 is carried after it has left the shower 17 and before it comes into contact with the web at the nip of the couch rolls 4 and 8. And I have also shown a lower pair of suction press rolls 27 through which the lower felt is carried after it has left the shower 25 and before it picks up the web at the nip of the suction press rolls 24.

The main advantages of these additional suction press rolls, located and operating substantially as described, are, that the web carries much less water when it is applied to the drier, and thus the machine may be run at a considerably greater speed, there is much less wear on the felts than where plain wringer rolls are used which require very high pressures and are less efficient in removing water, the life of the felts is increased.

creased, and less water is required for cleaning where the water is drawn out of the felts. Dirt is picked off the surface rather than forced into the interstices of the belt.

- 5 The term "pair of suction rolls" wherever used in the above description, is obviously intended to include any pair of cooperating rolls in which only one of the rolls is equipped with suction devices. In this art 10 such a pair of rolls is usually called a "pair of suction rolls."

I claim:

1. In a paper-making machine, web forming means, web drying means, a felt engaging the web between the forming means and the drying means, a felt washer, and a pair of suction pressure rolls engaged with said felt after the latter leaves said washer and before it makes contact with the web.
- 15 2. In combination with the web forming wire couch roll and drying cylinder of a paper-making machine, a pick-up felt and means for conveying the web into contact with the drying cylinder, a felt washer, and a pair of suction pressure rolls engaged with said felt between said washer and the point of pick-up of said felt with the web.
- 20 3. In combination with the web forming wire, drying cylinder, and transfer roll of a paper making machine, an upper felt conveying the web from the forming wire to the transfer roll, a lower felt and means for guiding the same into contact with the under side of the web between the forming wire and the transfer roll, washers for said felts respectively, and two pairs of suction pressure rolls respectively engaged with said felts at points between said washers and the points of pick-up of said felts with
- 25 40 said web.
4. In combination with the web forming wire, drying cylinder, and transfer roll of a paper making machine, an upper felt conveying the web from the forming wire to the transfer roll, a lower felt and means for guiding the same into contact with the under side of the web between the forming wire and the transfer roll, a pair of suction pressure rolls through which said felts with
- 45 50 the web between them pass, washers for said felts respectively, and two pairs of suction pressure rolls respectively engaged with said felts at points between said washers and the points of pick-up of said felts with
- 55 said web.

WILLIAM R. KELLETT.
